CONTINUOUS PROPANE DEWAXING

Ernest W. Thiele, Chicago, Ill., assignor to
Standard Oil Company, Chicago, Ill., a corpora-
tion of Indiana

Application December 30, 1936, Serial No. 118,383

2 Claims. (Cl. 62—114)

This invention relates to the separation of wax from oil and particularly to the separation of paraffin wax from mineral oil by the use of a liquefied normally gaseous diluent, such as propane, and it relates more particularly to a new and improved apparatus for carrying out this separation in a continuous manner.

It has been found that propane and other liquefied normally gaseous diluents, such as ethane, propane, butane, isobutane and mixtures of these are highly effective dewaxing agents. The necessary chilling can be accomplished readily in whole or in part by evaporation of a portion of the diluent or, in other words, by self-refrigeration. It has also been found that when this chilling operation is carried out by the sudden flashing of a portion of the diluent, the wax is thrown out of solution in a form which does not permit its efficient removal by filtering, settling or other means. Various methods and apparatus have been devised for the elimination of this shock chilling effect.

One type of apparatus heretofore proposed comprises a number of flash drums arranged in series, each two adjacent flash drums being connected by a single pipe containing a valve. The pressure drop necessary to accomplish the self-refrigeration takes place almost exclusively across the valves and even though the chilling is conducted in several steps by reason of the number of flash drums, serious shock chilling ensues. It has been proposed in Atwell Patent 2,006,011 to eliminate this difficulty by the use of a long restricted pipe giving a gradual pressure drop. My invention relates to a more practical, flexible and efficient apparatus for carrying out the method of the Atwell patent.

It is an object of my invention to provide a propane dewaxing apparatus which will be highly efficient and highly flexible, which will permit continuous operation and which will eliminate the difficulties inherent in flash chilling. Further and more detailed objects of my invention will become apparent as the description thereof proceeds.

The invention will be described with particular reference to a preferred embodiment thereof which is given by way of illustration and not by way of limitation. Various modifications will be apparent to those skilled in the art and are within the scope of my invention.

This preferred embodiment is illustrated in the accompanying drawing which forms a part of this specification and which shows my apparatus diagrammatically.

Referring now more particularly to the drawing, propane or other liquefied normally gaseous diluent from storage tank 11 passes therefrom through pump 12 and a combined heater and

is pumped from storage tank 14 by pump 15 into heater and mixer 13 wherein it is brought into solution in the propane, preferably at a temperature above that at which the wax is completely soluble. From the heater and mixer 13 the solution passes preferably to a surge drum 16 and then through one or more of a group of independent, long, restricted conduits C_1 arranged in parallel with each other. In these long restricted conduits there is a gradual pressure drop which results in a gradual and continuous vaporization of propane and gradual and continuous chilling. The parallel conduits C_1 discharge into a drum 17 from which the propane vapors liberated during the passage of the solution through the conduits C_1 are removed passing overhead through valve 18 and line 19 to a compressor 20 and condenser 21 and thus back to the storage tank 11. I prefer to use at least three conduits arranged in parallel.

Each of the long restricted conduits C_1 is equipped with a valve V_1 . Any one of these valves is always either open or closed—never throttled. In other words, there is no sudden pressure drop across a valve since this would result in the undesirable flash chilling effect previously mentioned. In order to produce a more or less uniform rate of chilling during the passage of the mix through the pipe, it will generally be found desirable to form each conduit of several sizes of pipe, increasing in diameter toward the exit end of the conduit.

By using a number of long restricted pipes in parallel, flexibility is secured and this flexibility is extremely important. At any given time one, two or any number of these pipes can be used, the remainder, if any, being shut off by the appropriate valves. It is highly desirable, although not completely necessary, that these conduits be different in size from each other since this greatly increases the flexibility of the apparatus. Thus, for instance, if the first conduit C_1 has a capacity taken as unity, the second conduit C_1 can have a capacity of two units, the third conduit C_1 a capacity of four units, the fourth conduit C_1 a capacity of 8 units and the fifth conduit C_1 a capacity of 16 units. With this arrangement it will be seen that by control of the various valves V_1 any given valve being either completely open or completely closed, thirty-one different capacities are available. In other words, the total capacity of the conduit system connecting surge drum 16 and drum 17 can be any integral number of units from one to 31.

While the various conduits C_1 can all be of the same length, it is preferred to apportion the lengths and diameters of the various conduits so that the course of the fall of the temperature and pressure through them will be the same. Moreover, it is desirable that the time which it takes

the mix to travel through each of the parallel conduits be the same, since the time determines the rapidity of crystallization, which in turn determines (with other factors) the character of the crystals. These conditions are fulfilled when the following relationships hold:

$$d = k_1 v^{3/7}$$

and

$$l = k_2 v^{1/7}$$

where d is the diameter of the conduit, l its length, v its capacity, and k_1 and k_2 are constants. It follows from these equations that:

$l = k_3 d^{1/3}$, or, in other words that the length varies with the cube root of the diameter. Thus if one of conduits C_1 has a diameter eight times as great as that of a second of conduits C_1 (to take a very extreme case) it should be twice as long and would have 128 times the capacity of the second conduit.

These considerations hold even when each conduit increases in size toward the exit end since the capacity is the same throughout the conduit. In this case, the diameter relationships referred to in the preceding paragraph must be taken in terms of diameters at corresponding points on the various conduits.

The liquid material from drum 17 carrying some wax in suspension passes through a second conduit system composed of conduits C_2 , similar to conduits C_1 of the first conduit system, connecting surge drum 16 and drum 17. The second conduit system discharges into drum 22, preferably below the liquid level therein.

I have illustrated an apparatus having two conduit systems and two discharge drums, i. e. two stages. It will, however, be understood that any number of stages can be used and in actual practice I prefer to use at least five or six sets of conduit systems and discharge drums, i. e. at least five or six stages, in order to permit the gradual removal of the liberated propane vapors. Otherwise the system tends to become loaded up with vapors and the capacity of the conduit systems is decreased.

Returning to drum 22 it will be seen that propane vapors are again removed overhead passing through valve 23, line 24, compressor 25 and condenser 21 back to storage tank 11. This compressor can be made large enough to take care of the vapors from drum 17 by opening valve 26 and passing them through the by-pass line 27 into line 24. In this case compressor 20 can be shut down or eliminated. The liquid from the last drum, carrying wax in suspension, passes through line 28 to a wax removal device or wax removal devices which may be filters, settlers or centrifuges. I prefer to use one or more continuous filters 29. Wax is continuously discharged from continuous filter 29 through line 30 and freed from propane by means not shown. The filtrate from continuous filter 29 is passed to a recovery system by means of pump 31. Preferably its capacity to absorb heat is utilized in the system. This can be done by passing the cold filtrate through a line 32 to a heat exchanger coil 33 arranged in the vapor space above drum 22. This serves to recondense some of the propane vapors and is equivalent to the introduction of additional cold propane into drum 22 to make up for the evaporation in conduits C_2 . It is also

possible, of course, to introduce makeup propane from storage tank 11 by means not shown. The filtrate then passes through line 34 to a second heat exchange coil 35 in the vapor space above drum 17 and thence through line 36 and heater 37 to still 38, which is preferably operated under considerable pressure. From the still, propane vapors pass to condenser 21 and back to storage tank 11. The oil, at least partially freed from propane, passes out of the bottom of still 38 through valve 39. In accordance with common practice still 38 is operated at a pressure of several hundred pounds per square inch in order to avoid recompression of the propane vapors. This results in the removal of some residual propane along with the oil through valve 39 and this can be removed by flashing and stripping in the conventional manner, but this is not shown.

The liquid levels in drums 17 and 22 are controlled by liquid level controllers 40 and 41 acting on valves 18 and 23 respectively.

It will be understood that in a propane dewaxing system there are a great many variables which make it highly desirable to have the utmost possible flexibility. Various wax bearing lubricating oil stocks are handled from time to time, various changes in the diluent composition are encountered, changes in the ratio of oil to diluent may become desirable, etc. Furthermore, in the actual operation of the system even with a fixed stock, a fixed diluent, a fixed diluent to stock ratio, etc. it becomes necessary to adjust the system from time to time in order to keep the various stages operating at the same rate and to produce the desired amount of cooling in each stage. This flexibility is completely lacking in apparatus of this type heretofore known.

While I prefer to do all my chilling in apparatus of the type described, it will be understood that a portion of the chilling can be conducted in other types of apparatus, for instance, by indirect heat exchange in scraped surface chillers. The more critical portion of the cooling operation should be conducted in the apparatus of my invention.

I claim:

1. Apparatus for dewaxing a wax-bearing mineral oil by the use of a liquefied normally gaseous hydrocarbon diluent, comprising means for dissolving said oil in said diluent, a plurality of friction-drop chilling stages to precipitate wax from said oil and means for removing the precipitated wax from the oil, each of said friction-drop chilling stages comprising a plurality of independent, long, restricted conduits adapted to accomplish friction-drop chilling and arranged in parallel with each other, said parallel conduits being of substantially different capacities, the larger of said conduits being relatively long and the smaller of said conduits being relatively short, shut-off valves to permit the selective use of any one or more of said parallel conduits, a vessel into which said conduits discharge, and means for removing diluent vapors from said vessel.

2. Apparatus according to claim 1 in which the respective lengths of said conduits are approximately proportional to the cube roots of their respective diameters at corresponding points.

ERNEST W. THIELE.
